UNITED STATES PATENT OFFICE

2,373,940

GLOVE

Herbert W. Beall, Mishawaka, Ind.

Application January 12, 1942, Serial No. 426,511

1-Claim. (Cl. 2—168)

This invention relates to gloves and more particularly to a preformed glove and the method of making the same.

A glove of the character designated is particularly desirable in enabling the aviator to manipulate the controls while his garment suit is subjected to internal pressure which is necessary for high altitudes for stratosphere flying. A glove of this nature forms an integral detachable part of an aviator's suit forming the subject matter of my copending application Serial No. 365,543, filed November 13, 1940, now Patent 2,335,475.

In gloves heretofore employed the fingers, for example, are formed straight and when the internal pressure is great the pressure on the glove tends to straighten out the finger portions and render them so rigid that it is physically impossible for the person to contract the fingers to grasp the controls or other controlling agencies in an aeroplane.

One of the important objects of the present invention is to provide a novel form of preformed glove which shall facilitate the movement of the aviator's hand while the suit is subjected to the desired pressure.

Another object of the invention is to provide a novel form of reinforced glove which shall be fluid-tight and maintain its form when subjected to relatively high pressure so that the person may have free use of his hands and fingers without muscular strain to overcome the glove resistance.

Another important object of the invention is to provide a novel method for making a glove of the character designated.

Another object of the invention is to provide a novel form of attachment joint for connecting the glove to an aviator's garment sleeve so as to provide a pressure seal as well as permit rotative or twisting movement of the hand relative to the aviator's forearm.

A further object is to provide a glove of the character designated having such shape, when subjected to pressure so that a person may grasp an object without muscular effort to overcome the strain inherent in the glove material when subjected to such pressure.

These and other objects of the invention will be more apparent from the following specification and drawings and more particularly set forth in the claim.

In the drawings:

Figure 1 is a perspective view partially in section of a preformed glove constructed and arranged according to the present invention;

Figure 2 is a sectional view illustrating steps in the formation of the glove;

Figure 3 is an enlarged sectional view of the layers of material on line 3—3 of Figure 1;

Figure 4 is a perspective view partially in section showing the palm reinforcing plate;

Figure 5 is a cross sectional view on line 4—4 of Figure 4;

Figure 6 is a perspective view of the palm plate;

Figure 7 is a sectional view on line 7—7 of Figure 1; and

Figure 8 is an end view of the glove connection shown in Figure 1.

Referring to Figure 1 of the drawings, there is shown a preformed rubberized fabric glove constructed and arranged in accordance with the present invention wherein it will be noted that the finger portions of the glove are preformed in a position to provide a fixed natural grasping position of the glove.

It will be understood that in the employment of this glove for aviation purposes for example, in which the aviator is subjected to artificial pressure conditions resulting from high altitude flying, it is necessary to provide a sealed garment which shall be subjected to internal pressure so as to provide a pressure differential on the body of the aviator in order that he may efficiently and effectively maintain conscious control of the aeroplane or the other agencies under his command.

Sealed gloves heretofore provided have been formed straight and when they are subjected to the required or desired internal pressure, the aviator must exert muscular effort to bend the glove fingers to grasp the controls of the aeroplane or the other navigational instruments or machine gun triggers, for example.

The novel form of glove is of rubber construction indicated generally by the numeral 1 and 40 appropriately reinforced with a silk fabric portion indicated by the numeral 2. The build up of the glove is illustrated in detail in Figure 3. Also formed in the glove is a preformed irregular curve-shaped metal palm member indicated by the numeral 3 specifically illustrated in Figure 6.

As indicated, this plate has a curved formation which extends over the palm and embraces the forefinger between the thumb, so that when the glove is subjected to substantial internal pressure the palm, fingers, and thumb portions of the glove maintain a fixed natural grasping position so that all that is required of the aviator is to move his arm to the appropriate controls and manipulate them as desired without muscular effort to overcome the resistance of the glove material.

As illustrated in Figure 1 of the drawings, the glove is preferably of the long sleeve type, so as to permit a maximum amount of wrist movement. The glove is attached to a garment sleeve, not shown, by a detachable metal joint connection 5 illustrated by the numeral 4.

The metal joint connection may be of any convenient type such as the bayonet joint and provided with an internal sealing ring indicated by the numeral 5 which functions to increase the sealing effect upon the increase of internal pressure. This increased sealing effect is provided by the increased area afforded by the inclined surface 6. In other words the construction provides for normal free movement of the person when subjected to ordinary atmospheric pressure existing at low altitudes. When the aviator ascends to such altitudes as 35 or 40 thousand feet, considerable internal pressure must be provided to counteract the change and as these pressures are provided the sealing effect is increased, and naturally the mobility of the person is decreased, because he is incased in a pressure garment which naturally tends to maintain a more rigid position and condition upon this increase of 10 internal pressure.

The first step necessary in the formation of a preformed glove is to provide a suitable collapsible core or form which can be removed, and this core is made by making a moulage mold of the object, i. e., the hand. As well known in the art, a moulage consists of a material conforming to the hand and may be stripped off without deleterious effects to the skin or mold. This makes a negative mold indicated by the numeral 7 and one upon which the positive mold may be made by pouring in postmoulage to form a positive mold. After the positive moulage mold is made it is dipped in a latex bath and coagulated and dried to begin the formation of a mold bag indicated by the numeral 8, Figure 2. The latex preferably contains Ethyl-Zymate as an accelerator. After the mold is dried it is then covered with a silk reinforcing fabric.

After this operation a covering of silk fabric is applied to the glove mold which has been sprayed with latex and a wetting agent and Ethyl-Zymate. After this operation the mold bag is again dipped in latex and a coagulant solution and dried as before. The bag thus formed by the repeated applications of material as above stated is now cured by heat to melt the postmoulage so that it may be removed from the mold bag.

The mold bag thus formed is now ready for attachment to a detachable base indicated by the numeral 9 and containing a valve for the inflation of the bag, which may be connected to any convenient source of air pressure, not shown.

Having thus formed the bag, it may then be repeatedly dipped in latex and coagulant to provide a heavier structure, if desired.

After the formation of the mold bag 8, as above described, it is now inflated to the desired size and treated with a non-adhesive substance for subsequent operation. This application of the non-adhesive substance prevents the first application of latex from adhering to the mold bag and thereby permits the ready removal of the glove when subsequently completed. It will be understood that the degree of inflation will change somewhat the size of the fingers in relation to the palm portion to provide an inflatable core upon which the glove may now be formed.

A suitable collapsible form having now been provided, the next step is to make a glove of the

5 desired configuration. The form 8 is dipped into a bath of latex and coagulant and dried in the same manner as that previously employed in providing the mold bag which now serves as the core for making the glove. After the latex applications, several courses of which may be employed, a silk fabric reinforcing material is now applied and the bag deflated. After the mold bag is deflated and the connection ring 9 removed, a rigid form stake (not shown) is inserted in the mold and the entire structure rolled by a suitable rigid implement (not shown) so as to firmly and uniformly adhere and unite the silk fabric to the latex. The stake form is then removed from the core and the core is then again inflated to the desired previous pressure.

10 After this operation the glove is reinforced by the addition of the preformed curve metal palm plate 3 is applied to the latex body. After the palm plate is applied it is covered by a heavy silk reinforcing material 11 which completely covers and extends beyond the palm plate 3 in all directions as shown in Figure 4. It being understood that the palm plate is initially secured to the latex material by a heavy latex cement. After the palm plate and the reinforcing material is applied to the glove material, the glove portion is then 15 finally dipped in latex to provide the desired covering. This final dipping operation may be repeatedly applied until the desired thickness of the glove is obtained and all the parts formed into a smooth and finished article for the purpose intended.

20 After the final dipping operation the mold is deflated and the glove stripped from the mold, and thus inherently maintains its desired pre-formed configuration.

25 In the form shown in Figure 1 it will be noted that the palm plate includes a palm projection portion 12 and a curved portion 13 extending between the thumb and first finger. These curved portions provide a rigid palm section which enables the hand to maintain a firm natural grasp on an object, when the glove is subjected to relatively high internal pressure, with a minimum of muscular effort.

30 Furthermore, the curvature of the finger portions in relation to the palm structure causes the thumb and fingers to in effect contract relative to the palm.

35 The feature of the proposed glove is that under normal atmospheric pressure conditions the flexibility of the materials enables the glove to be used in the regular way, but when subjected to pressure it resumes a preformed condition for which it is desired.

40 Having thus described a glove constructed in accordance with the present invention, it is obvious that various changes may be made therein without departing from the scope of the invention as set forth in the claim.

45 What I claim is:

46 As a new article of manufacture, an inflatable utility glove adapted to withstand internal pressure and having finger and thumb members, the thumb member preformed in fixed curved relation toward the finger members, means reinforcing the glove so that the fingers shall tend to contract relative to the thumb and increase the 50 grasping effect of the glove when internal pressure is applied to the glove, and a seal connection member for attaching the glove to a pressure garment sleeve for inflating the glove.
